PORTABLE BACK REST

Henry E. Dawkins and Sheldon T. Dodin,
New York, N. Y.

Application July 24, 1950, Serial No. 175,536

3 Claims. (Cl. 155—133)

1

This invention relates to a portable back rest for benches, seats and the like.

The principal object of this invention is the provision of a portable back rest which may be mounted on stadium benches and other benches which are normally without back rests, as well as on canoe and rowboat seats, and the like. It is a well-known and often painful fact that stadium benches at ball games and musical concerts are frequently most uncomfortable since they afford no support for the back. The present device is a portable back rest which may be carried to the ball game or musical concert and applied to a backless bench to serve as a back rest thereon. It is readily portable from place to place, and may very readily be mounted on the backless bench and may as readily be removed therefrom.

In the preferred form of this invention, the portable back rest comprises a frame of inverted U-shape and a pair of clamps which are connected to the legs of said inverted U-shaped frame. These clamps may be attached to the back edge of a backless bench in order to enable the frame to serve as a back rest therefor. The inverted U-shaped frame comprises a pair of inverted L-shaped members which are telescopically and detachably connected to each other. When said inverted L-shaped members are detached from each other and placed adjacent each other, they take up very little room and they may be inserted into a convenient bag or cover for carrying from place to place. This bag or cover may be described as a slip cover which may be slipped over the inverted U-shaped frame when said frame is clamped to a bench and thus span the gap between the legs of the frame to give support to the back of a user.

To give further comfort to a user, a resilient pad is carried within the slip cover and is so disposed therein that it covers the front of the frame when the slip cover is slipped over said frame. Hence, the pad serves as a cushion between the frame and the person whose back rests against the frame.

It is accordingly another object of this invention to provide a portable back rest of the character described which includes a frame that may be clamped to a bench and a pad for said frame which serves as a cushion between the frame and the person whose back rests against the frame, said pad being mounted within a slip cover which is adapted to accommodate the frame for carrying and storage purposes. The cover serves as a webbing to span the space between the legs of the frame and also as the means of supporting the pad on the frame when the frame is mounted in operative position on the back of a bench. The frame comprises a pair of detachably connected members which may be detached from each other to facilitate inserting into the cover

for carrying and storage purposes. Stated differently, the frame is of the knock-down or collapsible type which may be set up into operative position or collapsed or disassembled for insertion into the cover. The cover has a front wall and a back wall and it is closed along the top and two sides. It is open at the bottom and there provided with a slide fastener closure.

A preferred form of this invention is shown in the accompanying drawing, in which:

Fig. 1 is a perspective view of the cover of the back rest, showing said cover functioning in the manner of a container for said back rest frame members, and showing how the back rest is carried in disassembled condition.

Fig. 2 is a front view of the back rest showing it mounted on a bench and showing the cover mounted thereon and serving as a cushion therefor.

Fig. 3 is a vertical section taken on the line 3—3 of Fig. 2.

Fig. 4 is a side view of said back rest also showing how the back rest is mounted on a bench and how the cover serves as a cushion on said back rest.

Fig. 5 is a section on the line 5—5 of Fig. 4, showing how one of the clamps is swivelly connected to one of the legs of the frame of the back rest.

The portable back rest herein claimed comprises the following elements: a frame 10 of inverted U-shape, a pair of clamps 11 and 12 swivelly connected to the legs of said inverted U-shaped frame, and a slip cover 13 which has a pad 14 mounted therein. More specifically, inverted U-shaped frame 10 comprises a pair of inverted L-shaped members 20 and 21, respectively. These inverted L-shaped members may be made of tubular material, such as tubular aluminum, which is both strong and light in weight. One of said tubular members, say tubular member 20, may have a stud 22 projecting outwardly therefrom and adapted to enter the free end 23 of the other inverted L-shaped member 21. It is by this means that the two members 20 and 21 may be telescopically and detachably connected to each other. This telescopic connection may best be provided in the middle of the yoke portion of the inverted U-shaped frame 10. (See Fig. 2.)

Clamps 11 and 12 are identical and a description of one will suffice as a description of both. Taking clamp 11, therefore, which is shown in Figs. 2, 4 and 5, it will be seen that it is of the C-clamp variety. It has a top anvil portion 11a and a bottom screw-holding portion 11b. A bracket or arm 11c connects the two portions 11a and 11b. A thumb screw 11d having a swivel button 11e is screw threadedly engaged in hub portion 11b, and it may be worked toward and

away from anvil portion 11a. This clamp may be used in the same manner that C-clamps generally are used, and it is adapted to accommodate a board 30 of a conventional bench. The clamp engages the board between its anvil 11a and its swivel button 11c in the manner shown in Fig. 4.

Bracket 11c of the clamp has a hole 11f formed therein to accommodate one of the legs of the inverted U-shaped frame. It will be noted that said leg of the frame has a pair of cutouts 31 formed therein and that a pin 32 is connected to bracket 11c of the clamp and extends through said cut-outs 31 in the leg of the inverted U-shaped frame. This pin 32 prevents dislodgement of the leg of said frame from the clamp but it allows the clamp to swivel axially about the leg of the frame an angular distance of approximately 90°. This is an important feature since it enables the clamp to swing into parallel relation to the plane of the inverted L-shaped member to which it is connected, to facilitate insertion into the slip cover 13. (See Fig. 1.)

Clamps 11 and 12, like inverted L-shaped members 20 and 21, should preferably be made of aluminum, in this case cast instead of tubular aluminum, for purposes both of strength and the saving of weight. But other materials may also be used, if desired, such as magnesium or malleable iron. The same may be said of the tubular frame. Aluminum is not the only material that may be used. Other materials such as magnesium or tubular steel are also well adapted for the purposes of this invention.

Slip cover 13 should preferably be made of heavy, durable and water-proofed material such as rubberized canvas or duck. Slip cover 13 has a front wall 35 and a back wall 36 which is sewed thereto along the two sides and the top thereof. The bottom of the slip cover is left open and is provided with a slide fastener closure 37. (See Fig. 1.) Inside the cover is pad 14 as has above been indicated. This pad may be attached to the inside of the cover by the same means which is used to attach the front and back walls of the cover to each other. In other words, the pad may be sewed to the inside of the cover at the same time and by the same means that the front and back walls of the cover are sewed together.

When the slip cover is placed upon the inverted U-shaped frame of the back rest, the pad rests against the front of the frame and serves as a cushion between said frame and the person whose back rests against the frame, while the cover itself spans the gap between the frame legs. It is important that the cover be prevented from shifting on the frame. To insure against such shifting, a pocket is provided inside the slip cover, on the back wall thereto, and said pocket is so shaped and so dimensioned that it accommodates the inverted U-shaped frame without very much in the way of room or clearance to spare. In other words, the frame fits snugly in the pocket thus produced, and shifting of the cover relative to the frame is thereby prevented. This pocket is best shown in Fig. 3, and it is designated by means of the reference character 40. Pocket 40 is formed between back wall 36 of the cover and a panel or inner wall 41. This panel has the approximate shape of the inverted U-shaped frame, referring, of course, to the outline shape thereof. When said panel 41 is sewed along its two side edges and its top edge to the inside of

wall 36, pocket 40 is formed between said panel and said wall.

Fig. 1 shows how the portable back rest hereinabove described may be disassembled for storing in cover 13. It will there be seen that the two inverted L-shaped members which together comprise the inverted U-shaped frame may very conveniently be tucked into the cover 13 in the manner shown by means of the interrupted lines, after the clamps have been axially rotated from the position normal to the plane of the frame as seen in Fig. 4, to the position lying in the plane of the frame members as seen in Fig. 1. The slide fastener 37 may then be drawn to closed position and the cover accordingly serves as a bag or carrying case for the disassembled frame.

The foregoing is illustrative of a preferred form of this invention, and it will be clearly understood that said form may be modified in many ways and other forms may be provided within the broad scope and coverage of the invention.

Having thus described our invention, what we claim as new and desire to secure by Letters Patent is:

1. A portable back rest for benches, seats and the like, comprising a frame of inverted U shape, said frame consisting of a pair of members which are of inverted L shape and which are telescopically and detachably connected to each other, a C-clamp swivelly connected to the lower end of each of the legs of said inverted U-shaped frame for mounting said frame on the back edge of a bench or the like, and a cover which is removably mounted on said frame, said cover being provided with padding which serves as a cushion between said frame and the person whose back rests against said frame, said cover being sufficiently large, when the two inverted L-shaped members which comprise the frame are detached from each other and placed adjacent each other, to accommodate said inverted L-shaped members and the clamps which are connected to them, so that said back rest may conveniently be carried from place to place in said cover.
2. A portable back rest in accordance with claim 1, wherein the cover is provided with a slide fastener closure to hold the two inverted L-shaped members and their clamps therein.
3. A portable back rest in accordance with claim 1 wherein the cover is provided with a frame-receiving pocket behind the pad to receive the frame when it is set up in operative position and to prevent the cover and the pad from shifting relative to said frame.
